(57) **CLAIM**

The ornamental design for a front portion for analyzer table, as shown and described.

DESCRIPTION

FIG. 1 is a front perspective view of a front portion for an analyzer table in accordance with our new design;

FIG. 2 is a front elevational view of the front portion for the analyzer table illustrated in FIG. 1;

FIG. 3 a right side elevational view of the front portion for the analyzer table illustrated in FIGS. 1 and 2 with the left side elevational view being a mirror image thereof;

FIG. 4 is a top plan view of the front portion for the analyzer table illustrated in FIGS. 1-3; and,

FIG. 5 is a bottom plan view of the front portion for the analyzer table illustrated in FIGS. 1-4.

The broken line showing the environment in FIGS. 1-5 is for illustrative purposes only and forms no part of the claimed design relating to the front portion.
